CYLINDER RIDGE REAMER

Henry Robert Billeter, Highland Park, Ill., assignor to Ammco Tools, Inc., North Chicago, Ill., a corporation of Illinois

Application August 21, 1947, Serial No. 769,816

3 Claims. (Cl. 77—2)

1

This invention relates to reamers and it has to do more particularly with an improved cylinder ridge reamer of the type disclosed in United States Letters Patent No. 2,380,605 issued to Wallace F. Mitchell on July 31, 1945.

It is well known that wear occasioned by movement of piston rings along a cylinder wall surface tends to form a circumferential ridge adjacent the upper limit of ring travel. In installing pistons with new rings in old and worn cylinders, it is necessary that this ring-wear ridge be removed to insure proper and efficient operation. One of the objects of this invention is to provide an improved device for removing ring-wear ridges of the foregoing kind, which device is simple in construction, inexpensive to manufacture, and which is adapted for removal of ring-wear ridges in a foolproof and highly efficient manner.

Another object is to provide a tool of the foregoing type that eliminates chatter during the reaming operation regardless of the manner of its use by the operator.

A further object is to provide foolproof adjusting means for initially adjusting the ridge reamer a predetermined extent to insure the necessary operating freedom of the parts under conditions of maximum adjustment during the reaming operation.

Still another object is to provide a cylinder ridge reamer of the drag-cut type that will perform equally well when manually actuated by either a pull or push action.

A more specific object is to provide a ridge reamer with a resilient cutting blade by which the foregoing objects may be attained while providing a durable and long-lived tool easily operated with accuracy in the hands of unskilled labor.

Further objects and advantages will become apparent by reference to the descriptions and drawings wherein.

Figure 1 is an elevational view of a ridge reamer embodying my invention, the same being shown with its reamer blade in reaming relation to a ridge formed in a cylinder as a result of ring wear;

Fig. 2 is a horizontal section taken substantially on lines 2—2 of Fig. 1;

Fig. 3 is a longitudinal section taken substantially on line 3—3 of Fig. 2;

Fig. 4 is an enlarged partial longitudinal section taken substantially on line 4—4 of Fig. 1;

Fig. 5 is a partial section taken substantially on line 5—5 of Fig. 4;

Fig. 6 is an enlarged fragmental section show-

2

ing the reamer blade in position to remove the ring-wear ridge from a cylinder;

Fig. 7 is a separated, top plan view of the spring washer shown in Figs. 1, 3 and 4 employed as a stop for initially adjusting the tool a predetermined extent;

Fig. 8 is a diagrammatic view illustrating, for purpose of explanation, the negative rake angle for a reamer blade of the drag-cut type;

Fig. 9 is a perspective view of a modified form of reamer blade embodying my invention;

Fig. 10 is an enlarged fragmental section of a reamer embodying the modified form of reamer blade shown in Fig. 9;

Fig. 11 is a partial section taken substantially on line 11—11 of Fig. 10; and

Fig. 12 is an enlarged partial bottom plan view of the modified form of reamer blade shown in Figs. 9 to 11, inclusive.

Referring particularly to the tool shown in Figs. 1 to 7 of the drawings, it comprises two main sections 20 and 21. Section 20 rotatably supports section 21 and is adapted to be adjustably and rigidly clamped within a cylinder C of an internal combustion engine (not shown) at a position below the point where the ring-wear ridge R to be removed is formed. Section 21 supports a reamer blade 22 which is longitudinally adjustable toward and from the ring-wear ridge R, which blade involves an important feature of my invention as will be explained more fully hereinafter. Section 21 is provided at its top with a squared shank 23 for receiving a wrench (not shown) or other suitable power means for turning the section during the reaming operation.

Specifically, the section 20 is similar to the supporting section A of the aforesaid Mitchell Patent No. 2,380,605. Briefly, it includes a body member 24 having a plurality of radially disposed slots 25 in its underside adapted to slidably support clamping blade elements 26 for clamping section 20 to the cylinder wall. The body 24 is further provided with a concentric, hollow extension or hub portion 24^a on its upper or outer face which is rotatably mounted in a bore 21^b formed in the body 21^a of section 21.

Adjustment of the clamp blades 26 is accomplished by a rod 27 rotatably mounted in the sections 20 and 21, the lower end of which rod is threadably received in a clamping plate actuator 28. The rod 27 passes axially through the body 24 and its hub 24^a and axial displacement of it is prevented by a collar 29 secured to the rod 27 within the bore 21^b intermediate the sections 20 and 21, and a knurled hand adjusting

knob 30 secured to the top of the rod 27 for rotating it to raise or lower the clamping plate actuator 28. The knob 30 is disposed within a cage-like head 31 formed at the top of section 21, which head has an opening 32 in its side wall whereby the knob 30 is accessible to the workman for actuation to rotate the rod 27 to raise or lower the clamping plate actuator 28. The actuator 28 is provided with circumferentially disposed radial slots 33 for receiving the clamping plates 26, the bottoms 34 of such slots being inclined to provide camming surfaces which cooperate with complementally-shaped edges on the clamping plates 26 to cam the clamping plates 26 radially outwardly as the actuator 28 is moved upwardly by rotation of the adjusting knob 30. When the actuator 28 is lowered the clamping plates 26 are moved radially inwardly under the urge of a garter spring 35 so that the tool may be readily inserted into the cylinder C. Rotation of the actuator 28 relative to the body member 24 is prevented by a plurality of depending guide pins 36 secured in the body member and freely received in openings 37 in the actuator. A fixed axial relationship between the body member 24 and the rotatable section 21 is maintained by a spring-pressed ball 38 carried in a radially disposed bore in the section 21 which rides in a circumferentially disposed groove 39 in the hub of the body member 24.

From the foregoing, it will be apparent that the tool may be placed within the worn cylinder C and that the adjusting knob 30 may be rotated to cause the clamping plates 26 to move radially outwardly into contact with the worn portion of the cylinder wall, thus clamping the stationary section 20 of the tool substantially centrally with respect to the worn portion of the cylinder. It should be noted further that the rotatable section 21 is not influenced by the action of the clamping plates 26 but is free to rotate on the body member 24 and independently of the rod 27 and the adjusting knob 30.

The rotatable section 21 supports my improved reamer blade 22 for movement toward and from the ridge to be reamed. In accordance with my invention, the reamer blade 22 is formed of a high grade resilient material and is so supported that the cutting edge thereof flexes relative to the ridge to be reamed thereby relieving the cutting edge where there is a tendency to dig-in and chatter.

In former cylinder ridge reamers of the drag-cut type a rigid cutting bar or blade was employed. This is diagrammatically illustrated in Fig. 8, wherein a rigid cutter A having a rectangular outline (broken and solid lines) is shown in contact with an arcuate surface representing a ring-wear ridge. The angle X formed between the leading surface of the cutter A with respect to the direction of its rotation and a tangent drawn through the point of contact of the cutter's edge with the arcuate surface is known to those skilled in the art as the negative rake angle. The cutting rate of drag-cutters of this type is inversely proportional to the size of the negative rake angle. It follows necessarily that by reducing the negative rake angle stock is removed from the ring-wear ridge with greater speed. However, in prior tools of this character, as the negative rake angle is reduced the cutting edge of the tool tends to dig-in and chatter during the reaming of the ring-wear ridge. With the previous non-resilient cutters, the nega-

tive rake angle X was selected to provide satisfactory results without dig-in or chatter for most servicing operations. However, at times it became necessary to operate the tool in such a way that the driving force was applied rearwardly of the leading surface of the cutting bar with respect to the direction of its rotation. This meant that the cutting bar was in reality being pushed in the direction in which it was turning and at times it was found that the cutting edge would tend to dig in or chatter. When the operating force was applied forwardly of the leading edge of the cutter, or in other words the cutter was pulled rather than pushed, results were entirely satisfactory.

My novel resilient cutting blade has entirely eliminated any tendency to dig in or chatter during the reaming operation regardless of the manner of operation of the tool. This is accomplished because the projecting resilient portion of the reamer blade allows it to yield or to be relieved in a direction opposed to its direction of rotation when there is any tendency to dig in. The tool may be operated either with a push or a pull action applied to the squared end 23 of the rotatable section 21. Further, I have reduced the negative rake angle of my resilient reamer blade as diagrammatically illustrated in Fig. 8, wherein the negative rake angle is shown at Y. More particularly, I accomplish this reduction by giving the projecting cutting edge end of the blade a curved shape in which projects from the support 40 first rearwardly or in a direction opposite the direction of rotation and then forwardly and toward the cylinder wall at a decreased rake angle as indicated at Y (Fig. 8). In this manner, I have increased the cutting speed and at the same time have eliminated the dig-in or chattering of the reamer blade on the ring-wear ridge. In practice, I have found that a resilient reamer blade adapted for reaming of ridges in cylinders ranging from 2.60" to 4.250" in diameter, having a thickness of .050", $\frac{3}{4}$ " width and projecting approximately $\frac{1}{8}$ " beyond its supporting member does the job in an excellent manner. It is to be understood that these dimensions are given merely by way of example because it has been found that the dimensions of the blade and its extent of projection may be varied somewhat, so long as the projecting part retains the desired flexibility and resiliency to relieve the tendency to dig in and chatter.

The reamer blade 22 (Figs. 2 to 5, inclusive) is supported for movement toward and from the ridge to be reamed in such a way that it may be readily assembled and disassembled, and although it is formed of resilient material it is rigidly supported except at and adjacent to its cutting edge as above explained. More particularly, the blade 22 is carried by a rectangularly shaped supporting member 40 slidably mounted in a slideway 41 in the lower portion of the body 21a of section 21. The blade support 40 is provided on its outer face with a rectangular recess 42 of a depth and width substantially equal to the thickness and width of the blade 22. The blade is of such length that its forward end with the cutting edge projects beyond the forward end of its support 40 for engagement with the ridge R to be reamed. The blade 22 is further located on its support 40 by a dowel pin 43 (Figs. 4 and 5) on the support 40 which passes through an opening 44 in the body portion of the blade. In this manner the blade 22 is fully supported rigidly, except its cutting edge end, by its support mem-

ber 40. The outer wall of the slideway 41 is formed by a removable plate 45 (Figs. 1 and 4), the lower edge of which is received in a slot 46 in the lower part of body 21^a and its upper end is secured by a screw 47.

The blade support 40, and in turn the blade 22, is moved toward and from the ridge to be reamed by a vertically reciprocable actuator 48. Specifically, the body 21^a of section 21 is provided with a vertical bore 49 which intersects the slideway 41. The actuator 48, upper part 53 of which is cylindrical, is mounted in the bore 49 for vertical reciprocation. The lower portion of the actuator 48 is semicircular in cross-section and it has an inclined tongue or feather 51 which is engaged in a complementally inclined slot 52 in the adjacent face of the blade support 40 (Figs. 2 and 4). The upper cylindrical part 53 of the actuator 48 guides the lower part of the latter in the bore 49 so that upon upward movement of the actuator the blade support 40 and blade 22 are moved outwardly toward the ridge R and vice versa when the actuator is moved downward.

Reciprocation of the actuator 48 is accomplished through a threaded stem 53. The stem 53 extends upwardly and freely through an annular guide member 54 which closes the upper end of bore 49. The upper end of the stem 53 projects into a recess 55 (Fig. 3) formed in the section 21 between the lower side of the cage head 31 and the guide member 54. The upper projecting threaded end of the stem 53 is provided with a knurled adjusting nut 56 adapted for rotation on the stem 53 to raise or lower the actuator 48 and in turn the tongue 51 on the lower end thereof in accordance with the direction of rotation of the adjusting nut.

Adjustment actuation of the actuator 48 and blade support 40 is accomplished automatically through a coil spring 57 confined between the underside of adjusting nut 56 and the upper side of the guide member 54. The arrangement is such that when the tool is located in a cylinder, the nut 56 may be set up to a predetermined extent placing the spring 57 under a desired tension to automatically expand the blade 22 as the reaming operation progresses and to permit the blade and its support 40 to move back and forth freely or float so-to-speak as the reaming operation is carried out. To this end, a spring-washer-like member 58 is mounted upon the guide member 54. The washer member 58 is located on the guide member 54 by a plurality of depending peripheral lugs 59, one of which is long enough to seat against a flat seat 59^a formed on the body of section 21 immediately beneath the washer 58 to prevent rotation of the washer. The washer is confined against axial displacement by the spring 57, one end of which rests thereupon.

The washer 58 is provided on its upper face with a pair of diametrically opposed, resilient, upstanding fingers 60 (Figs. 4 and 7), the ends of which serve as stops to limit the extent the nut 56 may be screwed upon the stem 53 and, in turn, the extent of compression of the spring 57. The adjusting nut 56 is provided on its underside with a pair of diametrically opposed, depending lugs 61 (Figs. 3 and 4) which are adapted to engage the ends of the spring finger stops 60 as the nut 56 is screwed upon the stem 53. Although the lugs 61 engage the stops 60, the arrangement is such that the adjusting unit as a whole may float up and down (the lugs 61 sliding past the stops 60) to accommodate free movement of the blade 22 during the reaming

operation. The lugs 61 engage the stops 60 at a point approximately one and one-half turns of the nut 56 short of compressing the spring 57 to a solid condition, this being sufficient to effect full automatic operating adjustment of the blade 22 thereby permitting the necessary free floating action of the blade during reaming.

An expansion-limiting screw 62 (Figs. 1, 2, 5, and 6) is adjustably carried in the outer end of the blade support member 40, the purpose of which is to limit against the cylinder wall below the ring-wear ridge R when the ring-wear ridge has been removed sufficiently to bring it into flush relationship with the worn portion of the cylinder wall. This feature is more fully explained in the aforesaid Mitchell Patent No. 2,380,605.

The mode of operation of the structure so far described is as follows: The adjusting knob 30, as viewed from the top of the tool, is rotated counterclockwise causing the clamping blade actuator 28 to be lowered relative to the rod 27 permitting the garter spring 35 to draw the clamping plates 26 inwardly a sufficient extent to permit the stationary section 20 of the tool to be inserted within the cylinder. Before the tool is inserted in the cylinder, the adjusting nut 56 is rotated counterclockwise (as viewed from the top) and by contact of its top portion with the top wall of the recess 55, the actuator 48 is forced downwardly causing its tongue 51 to cam the reamer blade support 40 and the blade 22 inwardly sufficiently to allow the tool to be inserted in the cylinder. After the tool has been inserted in the cylinder a sufficient distance to align the reamer blade 22 with the ring-wear ridge R to be removed, the adjusting knob 30 is rotated clockwise causing the clamping plates 26 to expand outwardly into locking contact with the worn portion of the cylinder walls. The adjusting nut 56 is then turned in a clockwise direction which advances the reamer blade 22 radially outwardly into contact with the ring-wear ridge. When the blade 22 engages the ridge R, clockwise turning of the adjusting nut 56 is continued which compresses the spring 57 (Fig. 4) to spring press the cutting edge of the blade against the ring-wear ridge and causes the projections 61 of the nut 56 to engage the ends of the upstanding stop fingers 60 on the spring washer 58 whereby further clockwise movement of the adjusting nut and its axial movement downwardly caused thereby is prevented. Previous ridge reamers of this type did not employ means for limiting the adjustment of the nut corresponding to nut 56. In such devices it was customary to turn the adjusting nut clockwise until it limited on the top of a guide member corresponding to the guide member 54 and it was then backed off one and one-half to two turns for desired operating freedom of the parts. At times, the workmen using the former type of tool would fail to back off the adjusting nut the correct number of turns, or would forget to back it off at all, resulting in faulty operation of the tool or in causing an adjustment limiting screw like the screw 62 to score the cylinder walls. By employing the spring washer 58 and its resilient stop elements 60 in my improved ridge reamer, the extent of initial adjustment of the reamer blade may be predetermined without guesswork on the part of the operator and the proper deflection of the spring 57 will always be insured to accommodate reciprocation of the reamer blade due to variations in the cylinder wall surface.

The adjustment limiting screw 62 having been adjusted previously relative to the cutting edge of the reamer blade, the operator then proceeds to turn the rotatable section 21 of the tool and the resilient reamer blade 22 removes the ring-wear ridge without chatter and automatically advances outwardly under the control of the actuator 48 and the compression spring 57 as the ring-wear ridge is removed. When the ridge has been removed to the extent that it becomes flush with the cylinder wall, the round headed portion of the adjustment limiting screw 62 contacts the cylinder wall preventing further outward movement of the reamer blade. If the worn portion of the cylinder is not concentric with the ring-wear ridge, the adjustment limiting screw 62 prevents further cutting where the ridge has been removed to a flush relation with the cylinder but allows the blade to cut under the control of its spring-urged actuator where this condition has not been reached.

A modified form of resilient reamer blade 63 is illustrated in Figs. 9, 10, 11 and 12, which blade provides additional advantages. It will be noted that the blade 63 has an integral curved portion 64 which serves as a fixed limit or stop to determine the depth of cut on the ring-wear ridge R by contacting the worn portion of the cylinder wall C when the ring-wear ridge has been removed to a flush relationship with the worn cylinder wall. This eliminates the use of a separate stop 62 as used in the previously described form. The cutting edge of the modified blade 63 (Figs. 9 and 12), as well as blade 22 (Figs. 1 to 7), is disposed at a slight angle with respect to the ring-wear ridge R, tapering from its top point radially inwardly approximately 2° to cut a slight chamfer at the top of the cylinder wall as the ring-wear ridge is removed. The curved portion 64 is in parallel relation to the cylinder wall to provide a bearing surface sufficient to prevent scoring the cylinder wall. Further, it is located outwardly to an extent that a plane passed tangent to the curved portion 64 and perpendicular to the main body portion of the reamer blade will intersect the cutting edge of the blade substantially centrally with respect to its lateral cutting edge. Thus the curved fixed stop 64 not only substitutes for the adjustable expansion limiting screw 62 but it eliminates the necessity of adjustment when a new reamer blade is installed.

When the modified resilient blade 63 is used, a modified blade support member 65 (Fig. 11) is employed. The support 65 has two dowel pins 66 secured therein and adapted to enter transverse openings 67 (Fig. 9) in the blade for locating the blade relative to its support member so that the outer or cutting edge of the blade and the curved fixed stop 64 project outwardly beyond the end of the support member 65 a predetermined extent for engagement with the ring-wear ridge R. A notch 68 is provided in the modified blade 63 to separate its cutting edge from the stop 64 a sufficient distance to insure that the limit or stop 64 will be below the ring-wear ridge and to allow the cutting edge of the blade to flex without influencing such stop member. Except as hereinabove described, the modified form of Figs. 9 to 12 is similar in construction and operation to the form of Figs. 1 to 7.

I claim:

1. A cylinder ridge reamer comprising a pair of relatively rotatable sections one of which is adapted to be secured rigidly in the cylinder having the ridge to be reamed and the other of

which is rotatable on said first section and has a slideway therein and serves as a reamer blade carrier, a rigid blade support including a generally rectangular block slidable in said slideway in a generally radial direction toward and away from the cylinder wall, a reamer blade formed from a substantially rectangular sheet of thin resilient material of uniform thickness having a planar body portion and a cutting edge portion at one end formed with an arcuate portion transversely of the blade whereby the leading face of the edge portion constitutes a cutting face inclined forwardly with respect to the corresponding face of the body portion, said blade being disposed in abutting face-to-face relation with and rigidly supported between the leading face of said support and the corresponding face of said slideway with its cutting edge portion projecting beyond the ends of said support and slideway for yielding engagement with the ridge to be reamed, interengaging means in said blade and on the leading face of said support for holding said blade and support against relative movement and for sliding movement as a unit, a cam element in the trailing face of said support, and constantly active actuator means carried by said second section for resiliently urging said support outwardly and including a cam element interengageable with the cam element of said support.

2. In a tool of the type described, means for supporting the tool in a cylinder, a rotatable unit carried by said means including a reamer blade of the drag cut type, a support for said blade, an actuator for said support for moving it together with said blade toward and from the work, said blade comprising a single sheet of resilient metal and having a main body portion with longitudinal edges thereof disposed in parallel relation, a cutting edge first end portion disposed along a first part of one end of said body portion and inclined to the longitudinal edges, an arcuate shaped second end portion disposed along a second part of said one end and removed from said first end portion so that the cutting edge of said first end portion projects outwardly in such a way that a plane passed tangent to the arcuate portion and perpendicularly to the main body portion will intersect the cutting edge substantially centrally therewith, a leading face of said cutting edge being disposed at an obtuse angle with the main body portion to provide a negative rake angle less than if said leading face of said cutting edge portion were extended parallel with said body portion, and means on said main body portion for positioning said blade removably on said support with its cutting edge projecting from said support and free to flex in a direction opposite to the direction of rotation of the tool, and means for adjusting said actuator and support to control the reaming action of said blade.

3. In a cylinder ridge reamer of the type having a rotatable section supporting a reamer blade for movement toward and from the ridge to be reamed, means for adjusting and automatically expanding the reamer blade prior to and during the reaming operation which comprises a reciprocable blade actuator, a guide support for said actuator, a threaded extension on said actuator projecting through and beyond said support, an adjusting nut on the projecting end of said extension, a spring between said support and nut tending normally to move said actuator to expand said blade, the expanding action of said spring being varied by adjusting said nut upon

said extension to compress said spring more or less, and means for limiting the extent of adjustment of said nut and compression of said spring comprising a stop member mounted on said support and having a pair of axially yieldable and diametrically opposed stop fingers, and diametrically opposed stop elements on said nut adapted to simultaneously abut said stop fingers when said nut has been adjusted on said extension a predetermined extent in spring compressing direction but short of a position of complete compression of said spring and positively prevent further adjustment of said nut in spring compressing direction, said stop fingers and elements abutting each other in lateral direction and being free to reciprocate relatively axially of the tool.

HENRY ROBERT BILLETER.
